UNITED STATES PATENT OFFICE.

ABRAHAM M. DELLINGER, OF LANCASTER, PENNSYLVANIA.

GRINDING-MILL.

No. 858,267.

Specification of Letters Patent.

Patented June 25, 1907.

Application filed April 15, 1904. Serial No. 203,309.

To all whom it may concern:

Be it known that I, ABRAHAM M. DELLINGER, a citizen of the United States, residing at Lancaster, in the county of Lancaster and 5 State of Pennsylvania, have invented certain new and useful Improvements in Grinding-Mills, of which the following is a specification, reference being had therein to the accompanying drawing.

10 This invention relates to grinding disks used in mills and has for its object to improve the same in simplicity, cheapness of manufacture and efficiency.

To this end, my invention consists in the 15 construction hereinafter more particularly set forth and claimed.

In the accompanying drawing, Figure 1 represents a plan of a grinding disk embodying my invention; Fig. 2 represents a cross section of the same on line A—A of Fig. 1; Fig. 3 represents a top perspective view of a broken out section of the disk; Fig. 4 represents an edge view of a portion of the disk; and Fig. 5 represents a section on line B—B 25 of Fig. 1.

In said drawings, 6 designates the disk having an inclined bosom 7 and a land 8 concentric therewith in a plane at right angles to the axis of the eye. The said bosom is provided with a series of groups of parallel approximately tangential furrows 9 and intervening ribs 11 following the inclination of said bosom to the eye 13. The said land is provided with a series of similar groups of 30 parallel furrows 10 and intervening ribs 15 which are finer than those before mentioned and in the plane of said land. A series of

raised feed drifts 12, arranged at intervals on the bosom at the edge of the eye, having horizontal tops and vertical sides, leave between them on said bosom passages or conveyer flights deepening inwardly. The outer edges of these feed drifts are inclined inward in the direction of rotation, which is indicated by arrow 16. All the furrows and ribs incline 45 inwardly in this direction. In making this disk I cast the feed drifts 12, furrows 9 and sharp edged ribs 11 of the bosom, but leave the land in such casting without ribs or furrows. I then grind the land smooth and cut 50 therein the furrows 10, sharpening the intervening ribs 15, so as to get sharper and more regular and even ribs and furrows in said land than would be practicable by casting.

Having thus described my invention, what 55 I claim as new and desire to secure by Letters Patent is:

1. A grinding disk having feed drifts and groups of parallel ribs cast on the bosom and narrower groups of finer and substantially 60 parallel ribs cut upon the land.

2. A grinding disk having an inwardly inclined bosom provided with groups of parallel ribs and feed drifts raised at intervals about its eye, leaving passages or conveyer 65 flights between them, said blocks having horizontal tops and outer edges which incline inwardly in the direction of rotation and a land provided with groups of finer and substantially parallel ribs as above set forth.

ABRAHAM M. DELLINGER.
